UNITED STATES PATENT OFFICE.

ERNEST AROLAN, OF KINGSTON, NEW YORK.

CONDIMENT-SHAKER.

1,224,699.

Specification of Letters Patent.

Patented May 1, 1917.

Application filed October 19, 1916. Serial No. 126,519.

To all whom it may concern:

Be it known that I, ERNEST AROLAN, a citizen of the United States, residing at Kingston, in the county of Ulster and State of New York, have invented new and useful Improvements in Condiment-Shakers, of which the following is a specification.

My invention relates to new and useful improvements in condiment shakers, and has for its object to provide an exceedingly simple and effective device of this character, whereby two condiments, such as salt and pepper, may be supplied from a single receptacle.

15 A further object of the invention is to provide a perforated cap or closure for each end of a receptacle having means, whereby said cap is normally held closed to prevent the spilling of the contents of the receptacle when not in use, or to prevent shaking out one of the condiments when the other condiment is being used.

A still further object of the invention is to provide a perforated cap or closure having a central depression and three radiating depressions, the latter adapted to engage the end of the receptacle when the closure is in position, whereby an even contact is made with the end of said receptacle, said closure having a lug formed therefrom in the region of one of the radial depressions, said lug being bent outward and the hole left thereby overlying the end of the receptacle, said central depression having a perforated closing plate arranged therein and provided with a projection to which one end of a spring is fastened, the opposite end of the spring being attached to a lug on the cap for normally holding the perforations in the closing plate out of alignment with the perforations in the closure, said closing plate being further provided with a handle situated in one of the radiating depressions for operating the closing plate.

45 With these ends in view, my invention consists in the details of construction and combination of elements hereinafter set forth and then specifically designated by the claims.

50 In order that those skilled in the art to which this invention appertains, may understand how to make and use the same, I will describe its construction in detail, referring

by numeral to the accompanying drawing forming a part of this application, in 55 which—

Figure 1, is a side elevation of a condiment shaker made in accordance with my improvement.

Fig. 2, is a vertical sectional view thereof.

Fig. 3, is an end view thereof.

Fig. 4, is an enlarged sectional view of the

closing plate; and

Fig. 5, is a segmental sectional view of

the cap, showing the manner in which the 65

projection is made therefrom.

In carrying out my invention as here embodied 2 represents a receptacle of any suitable size, shape and material having a central bore or cavity 3 divided into two 70 compartments 4 and 5 by an integral partition 6, the latter being preferably smaller in capacity than the former and adapted to hold the condiment which is generally least used.

75 Each end of the receptacle is provided with external threads 7 on which are mounted the caps 8. Each cap consists of an end wall 9 and a flange 10 provided with threads 11, and the end wall is provided with a 80 central depression 12 having perforations 13 therein and a number of radiating depressions 14 preferably three in number, which are on the same plane as the central depression and act as seats for engagement 85 with the end of the receptacle when the cap is threaded thereon. Within the central depression is rotatably mounted the closing plate or disk 15 having perforations 16 therein and held in place by a pivot 17 or 90 its equivalent which passes through the closing plate and the central depressed portion of the cap.

From the closing plate projects an operating handle or lever 18, the sides of which 95 are turned up to produce flanges 19 and having its end turned over as at 20 to meet the flanges, thereby eliminating the sharp edges which might have a tendency to injure the person using the same. The handle 100 or lever 18 operates within one of the radial depressions and projects a short distance beyond the outer circumference of the cap, so that it may be readily and quickly actuated, and the upstanding walls on each 105 side of the depressions act as stops to limit

the movements of the operating handle or lever, so that the action of the closing plate is regulated.

The closing plate is provided with an integral projection 21 at its periphery, and to this is secured one end of the spring 22, the opposite end being secured to a lug or projection 23 cut from one of the radial depressions of the cap and bent outward as plainly shown in Fig. 5, and this lug or projection is so situated that the hole 24 formed by producing said lug is closed by the end of the wall of the receptacle, so as to prevent the condiment from accidentally spilling from the receptacle.

When the condiment shaker is standing upon a table or other object, those portions of the caps between the radial depressions act as feet, and the operating parts all lie below their outer faces. To use one of the condiments it is only necessary to actuate the closing plate by forcing the operating handle or lever against the action of the spring, when the perforations in the closing plate will be brought into alignment with the perforations of the cap, thereby permitting the condiment to be removed from the receptacle, and when sufficient condiment is obtained the operating lever is released at which time the closing plate will be rotated in the opposite direction by the spring, thus closing the perforations in the cap. Either of the condiments in the receptacle may be removed in the manner above stated, and while one of the condiments is being used, the other cannot be accidentally spilled because the closing plate on the cover at the end of the receptacle not being used, will be in its closed position.

Of course I do not wish to be limited to the exact details of construction as herein shown, as these may be varied within the limits of the appended claims without departing from the spirit of my invention.

Having thus fully described my invention, what I claim as new and useful, is—

1. A condiment shaker comprising a receptacle provided with external threads at each end thereof and having the interior thereof divided into two compartments, a cap for each end of the receptacle, each cap consisting of an end plate having a central perforated depression and a plurality of other depressions radiating therefrom, said radiating depressions engaging the end of

the receptacle to position the cap, a threaded flange formed integral with the end plate, a perforated closing plate rotatably mounted in the central depression, and means for holding said closing plate in its closed position.

2. A condiment shaker comprising a receptacle provided with external threads at each end thereof and having the interior thereof divided into two compartments, a cap for each end of the receptacle, each cap consisting of an end plate having a central perforated depression and a plurality of other depressions radiating therefrom, said radiating depressions engaging the end of the receptacle to position the cap, a threaded flange formed integral with the end plate, a perforated closing plate situated in the central depression, means for pivoting said plate in position, an operating handle formed integral with the closing plate and situated in one of the radial depressions, and means for normally holding said closing plate in its closed position.

3. A condiment shaker comprising a receptacle provided with external threads at each end thereof and having the interior thereof divided into two compartments, a cap for each end of the receptacle, each cap consisting of an end plate having a central perforated depression and a plurality of other depressions radiating therefrom, a threaded flange formed integral with the end plate, a perforated closing plate situated in the central depression, means for pivoting said plate in position, an operating handle formed integral with the closing plate and situated in one of the radial depressions, said handle having flanges formed with its sides and end, a lug formed integral with the edge of the closing plate, another lug formed from the cap in the region of one of the radial depressions, said lug being bent outward and the hole left thereby overlying the end of the receptacle, and a spring having its ends fastened to said lugs for normally holding the closing plate in its closed position.

In testimony whereof, I have hereunto affixed my signature in the presence of two subscribing witnesses.

ERNEST AROLAN.
